UNITED STATES PATENT OFFICE.

LUCIEN F. BRUCE, OF SPRINGFIELD, MASSACHUSETTS.

MAGAZINE FOR FIREARMS.

SPECIFICATION forming part of Letters Patent No. 708,311, dated September 2, 1902.

Application filed September 16, 1901. Serial No. 75,507. (No model.)

To all whom it may concern:

Be it known that I, LUCIEN F. BRUCE, a citizen of the United States of America, and a resident of Springfield, in the county of 5 Hampden and State of Massachusetts, have invented certain new and useful Improvements in Magazines for Firearms, of which the following is a full, clear, and exact description.

10 This invention relates to improvements in the magazines of military rifles—such, for instance, as the Mauser or the new military rifle now in course of construction by the United States Government at the Springfield 15 arsenal.

20 The type of magazine to which the invention pertains is characterized by the inclusion therein of a spring-supported follower or platform having the capability of an upward-and-downward motion with and against the spring, the downward motion of the platform being with the compression of the spring when a pack of cartridges is forced into the magazine, as well known.

25 The invention is illustrated in the accompanying drawings, in which—

Figure 1 is a central longitudinal sectional view through a portion of the firearm comprising the magazine which is constructed 30 with the features constituting the present improvements and having shown in conjunction therewith a cartridge-clip and the five cartridges which are understood as having been brought thereby in position over the 35 magazine being also shown, it being understood that the cartridges are shown as in the act of being forced downwardly into the magazine. Fig. 2 shows a slight modification.

40 It being perceived in the magazine shown that the follower or spring-supported platform *a* is carried at the upper leaf of the spring *b*, the several leaves of which have zigzag relations, and it being understood that the pressure in the downward direction 45 against the row of cartridges *x* to force them down into the magazine-chamber *d* is usually at about the point *y* adjacent the clip *z* and near the rear end portion of the magazine and of the follower *a* therein, such pressure naturally exerts the tendency to tilt the follower by its rear end downwardly and its forward end upwardly, correspondingly up-

wardly tilting the cartridges, so that the last or upper cartridge and sometimes the last two cartridges have their forward ends so far elevated as not to be brought for retention substantially level in the magazine to be thrown by the bolt with certainty into the barrel and it is the object of this invention to provide within the wall, at the rear portion of the 55 magazine-chamber, an abutment or shoulder against which a rear end portion of the follower may impinge, and which abutment momentarily constitutes a fulcrum for the follower, so that the further downward pressure 60 imparted against the pack of cartridges and through them to the follower will insure properly the depression of the follower and the cartridges, this provision, however, in no wise interfering with the facility of the introduction of all of the cartridges entirely into the 65 magazine-chamber.

Particularly referring to the drawings, *f* represents the rear wall, and *g* the forward wall, of the magazine, and *h* the plate which constitutes the base thereof, and to the said base-plate the lower leaf of the spring is engaged, the upper leaf being engaged with the follower, and all so that by the several intermediate spring-leaves, as required for proper range of distention, the floated follower is susceptible of quite wabbly motions.

The rear wall *f* of the magazine-chamber suitably well down toward the bottom is provided with the ledge or shoulder *i*, forwardly protruding, the wall continuing from said shoulder to the base of the magazine being about vertical, as indicated at *j*, or in any event not receding rearwardly, this formation precluding any liability of the rear end of 85 the follower catching under the protuberance at or below *i* to interfere with the free rising motion of the follower.

Inasmuch as the length of the magazine-chamber is but very slightly in excess of the 90 length of the cartridges and in order that there may be ample space for occupancy of the cartridges in the bottom of the magazine, the forward wall *g* at the lower portion thereof, as indicated at *m*, is recessed or "freed out."

100 The means for acquiring the greater certainty or reliability in the introduction of the cartridges into the magazine described and explained adds little, if anything, to the la-

bor and cost of construction and has been found in practice to be entirely efficient.

To facilitate ease of the action between the abutment and the rear end of the follower, 5 the abutment may be constituted by a roller i^2 , as shown in Fig. 2, or the contacting end portion of the follower might be constituted by a roller.

Having thus described my invention, what 10 I claim, and desire to secure by Letters Patent, is—

1. In a magazine for firearms of the character described, the magazine-case having the 15 loosely-mounted and spring-supported follower therein and having its rear end wall provided at a distance below its top, and somewhat above its bottom with a forwardly-protruding shoulder, against which the rear end portion of the follower in its descending 20 movement may contact, for the purpose set forth.

2. In a magazine for firearms, of the character described, the magazine-case having the loosely-mounted and spring-supported fol-

lower therein, and having its rear end wall 25 provided with a forwardly-protruding shoulder or ledge, at a distance above the bottom of the magazine-chamber, and said rear wall at all points below said ledge being as forwardly prominent as the ledge.. 30

3. In a magazine of the character described, the magazine-case having the loosely-mounted and spring-supported follower therein, the rear end of which is adjacent the rear wall of the case, and said rear wall being provided, 35 above its bottom, with a forwardly-protruding shoulder; said rear wall below said shoulder being as forwardly prominent as the shoulder, and the lower portion of the forward wall of the chamber being forwardly recessed for the 40 purposes set forth.

Signed by me at Springfield, Massachusetts, this 7th day of September, 1901.

LUCIEN F. BRUCE.
